UNITED STATES PATENT OFFICE

121,860

DESIGN FOR A PANTIE-GIRDLE

Abraham N. Spánel, New York, N. Y.

Application May 11, 1940, Serial No. 92,303

Term of patent 14 years

To all whom it may concern:

Be it known that I, Abraham N. Spánel, a citizen of the United States and a resident of New York, New York, whose post office address is 1100 Park Avenue, in the city, county, and State of New York, have invented a new, original, and ornamental Design for a Pantie-Girdle, of which the following is a specification, reference being had to the accompanying drawing, forming part thereof, wherein the figure is a front elevational view showing my new design for a pantie-girdle. The back, within the outline as shown, is conventionally plain except for the arrangement of perforations as shown, which pass through both the front and back.

I claim:

The ornamental design for a pantie-girdle, as shown and described.

ABRAHAM N. SPÁNEL.
